Nov. 15, 1932.

J. CARR

DRESS

1,887,867

Filed Dec. 10, 1930

Fig. 1

Fig. 2

INVENTOR.
BY Janet Carr
ATTORNEYS.
Albert L. Haen

UNITED STATES PATENT OFFICE

JANET CARR, OF LOS ANGELES, CALIFORNIA

DRESS

Application filed December 10, 1930. Serial No. 501,295.

This invention relates to and has for an object the provision of an improved type of dress, particularly adapted to be worn as an outer garment or uniform by women operators, workers, nurses, and the like.

An object is to provide a simplified pattern which may be economically and readily made into a one-piece garment, and may be put on or taken off of a wearer with facility.

An object also is to provide a uniform or a dress arranged in the form of a one-piece garment and provided with outer and inner front portions and a single back portion, with sleeve and neck openings, and means for attaching the front and back portions together for preventing the exposure of the under-clothing or limbs of the wearer. In this connection it may be understood that in the usual types of uniform or outer garment the openings are made either at the side or front, and the edges of the garment at the opening but slightly overlap, which, when the garment is worn, frequently exposes the under-garments or limbs unnecessarily.

In order to obviate the above mentioned conditions, and at the same time to provide a simplified form of garment, I permanently attach the back portion and the inner front portion together at one side by means of a seam extending down a side of the garment and detachably connect the same at the other side, and provide short sleeves and a neck opening in said portions.

To the opposite side of the back portion I attach a supplementary outer front portion by means of a seam extending entirely down the side, which is of corresponding length to the inner front portion, and has a waist portion which gradually increases in width from the shoulder downwardly to the belt line, and a skirt portion depending from the belt line. This supplementary front portion completely overlaps the inner front portion from the belt line downwardly to the bottom of the skirt and is provided at the waist line with an elongated narrow belt-like extension which extends around the back and is attached to the side of the garment remote from its point of beginning.

Ordinary snap fastenings are employed for attaching the inner and outer front portions together, and a button or other suitable fastening may be employed for attaching the belt extension to the back portion.

I have illustrated a preferred form of my improved dress in the accompanying drawing, in which

Fig. 1 is a front view with the dress entirely closed and the margins thereof suitably fastened together.

Fig. 2 is a similar view with the supplementary or outer front portion drawn upwardly so as to expose the inner front portion.

As hereinbefore briefly described, the dress includes an inner front portion 1, a back portion 2, and a supplementary or outer front portion 3. The portions 1 and 2 are permanently attached together at a side seam 4, as shown in Fig. 1, at the left side of the garment, and said portions 1 and 2 may be subdivided into waist and skirt portions, as at 5 and 6 respectively.

The waist portion of member 1 is permanently joined to the back portion 2 at a shoulder seam 7 on the left hand side of the garment, while the waist portion of member 3 is permanently joined to the back portion 2 at a shoulder seam 8 on the right hand side of the garment.

Sleeves 9 and 10 are attached to the opposite side of the garment, as shown, and are joined to the waist portions of the garment at seams 11 and 12 respectively. A central neck opening 13 is provided in the upper portion of the garment and includes a band 14 which surrounds said opening, the ends of which are adapted to be detachably fastened together by means of a snap, as at 15, or otherwise.

The outer front member 3 has a biased portion 16 and a skirt portion 17 which depends therefrom, as shown in Fig. 1. The portion 16 completely overlaps the right shoulder and side of the front portion 5 of member 1 and is provided with a downwardly flaring biased margin 18 which leads from the snap 15 downwardly and outwardly from the upper right hand side of the garment to the left hand side of the garment at the waist line,

55

60

65

70

75

80

85

90

95

100

and serves to only partially cover the front of portion 5. Portion 5 is additionally fastened beneath the shoulder seam 8 to the back portion 2 by means of a snap 19 or otherwise.

5 The member 3 also includes a belt-like extension 20 which extends around the back from the left hand side of the garment as a continuation of the portion 16, and is attached at or near the right hand edge 21 of the back portion 2 by means of a button 22 or otherwise. The back portion 2 may be also additionally attached to the right hand edge of front portion 5 by means of a snap 23 or otherwise.

10 15 It will be obvious that when the snap fastenings 15, 19 and 23 and the button 22 are detached from their respective portions of the garment the garment may be completely opened from the neck to the bottom of the skirt so that it may be readily put on over the outer or under clothing of a person, and as readily attached together at said fastenings. The fastenings are so arranged that the portion 6 of the inner front member 1 will be 20 25 completely covered by the supplementary portion 17 of member 3, and there will be no openings at the side or front of the skirt which under any conditions would render the under-clothing or limbs of a person 30 visible.

35 The belt-like extension 20 which extends entirely around the back 2 when buttoned at 22 serves to hold the back inwardly against the body and provides a more gracefully fitting garment and less smock-like than would be possible with the usual garment worn by workers, and at the same time obviates the necessity of wearing a belt with the garment, which is sometimes done. From the foregoing 40 description it will be understood that the back portion 2 may be cut in one piece extending from the shoulder seams downwardly to the bottom of the skirt, and the front waist portion 5 and front skirt portion 6 may 45 similarly be cut in one piece or in two pieces, as desired, and joined at the waist-line if cut in two pieces. In any event, the portions 5 and 6 are permanently attached at the left side of the garment to the back portion 2 at 50 the seam 4, which seam extends downwardly from the sleeve opening to the bottom of the skirt. The front portion 5 is also permanently attached to the back portion at the shoulder seam 7. The right hand shoulder 55 of portion 5 is detached at the top of the shoulder from the back 2, and the neckband 14 is open at a corresponding point. Thus the portion 5 may be detachably secured at the shoulder line to the back portion 2 by 60 means of the snap fastener 19. The upper front portion 16 and the corresponding skirt portion 17 of the supplementary front 3 are permanently attached at the right hand side of the garment to the back portion 2, and the 65 portion 16 is detachably secured at the shoulder and near the neckband 14 to the underlying portion 5. Also, by means of the snap fastening 23 the supplementary portion 3 may be detachably secured at the right hand side of the garment to the corresponding margin 70 of the inner front 1, while the belt 20 is extended around and outwardly over the back 2 and is detachably secured at the right hand side of the garment by means of a button or other fastening 22.

75 Thus it will be observed that when the garment is positioned on a person for use the supplementary front portion 16 completely overlaps the shoulder and side of the underlying front portion 5 while the margin 18 is cut on a bias so as to only partially overlap the front portion 5 above the waist-line. The portion 16 is cut, however, so that the covering area of the supplementary front portion is gradually increased downwardly from the right 80 hand shoulder to the waist-line, while the supplementary skirt portion completely overlaps the underlying skirt portion of the main front 1.

85 90 The advantages of my garment will be apparent to those skilled in the art of dress and uniform making, and while I have shown but one embodiment of my invention, it will be understood that I conceive it to be possible to modify the form of garment shown 95 within the scope of the appended claims without departing from the spirit thereof.

95 What I claim is:

1. A dress comprising main, back and front portions permanently secured together at one 100 side of the garment and at a corresponding shoulder and open at the other side of the garment from the neck to the bottom of the skirt, and a supplementary front permanently secured to the back and detachably secured to the shoulder on the open side of the garment, means for attaching the front and back together at said opening at a plurality of points, said main, back and front, and said supplementary front each including a waist 105 portion and a skirt portion, the waist portion of the supplementary front formed to completely cover the lateral portion of the waist of said main front adjacent said opening, and the skirt portion of said supplementary front formed to cover all of the skirt portion of the underlying main front, and a narrow extension formed as a continuation of said supplementary front and extending entirely around and attached to said back portion adjacent the juncture of said back and supplementary front.

115 120 125 130 2. A garment comprising a back, an inner front joined to the back at one side and also joined to a shoulder on such side, said inner front being detached from the back at the opposite side of the garment to provide an opening from the neck to the bottom of the skirt, said front comprising a waist portion and a skirt portion, said waist portion being de-tachably connected on the open side of the garment and at the corresponding shoulder with said back portion, and an outer front permanently attached to the back at the open side of the garment and including a waist portion detachably secured to the inner front portion at the shoulder and biased downwardly in the direction of the closed side of the garment so as to completely cover the inner front portion adjacent said opening and to partially cover said inner front portion at the front and on the closed side of the garment, said outer front having an extension continuing therefrom at the waistline and extended around said back, and means for detachably securing the free end of said extension to the garment.

JANET CARR.

20

25

30

35

40

45

50

55

60

65